(57) **CLAIM**

The ornamental design for a charging station, as shown and described.

DESCRIPTION

FIG. 1 is a front perspective view of a first embodiment of the charging station;

FIG. 2 is a front elevation view thereof;

FIG. 3 is a top view of the charging station shown FIGS. 1 and 8;

FIG. 4 is a left side elevation view of the charging station shown in FIGS. 1 and 8;

FIG. 5 is a rear view of the charging station shown in FIGS. 1 and 8;

FIG. 6 is a right side elevation view of the charging station shown in FIGS. 1 and 8;

FIG. 7 is a bottom plan view of the charging station shown in FIGS. 1 and 8;

FIG. 8 is a front perspective view of a second embodiment of the charging station; and,

FIG. 9 is a front elevation view of the charging station shown in FIG. 8.

The broken lines showing the remainder of a charging station are directed to the environment.

The broken lines shown on the front of the charging station are for the purpose of illustrating elements of the charging station that form no part of the claimed design. The broken lines shown on the top, bottom, rear, and sides of the charging station are for the purpose of illustrating environment, and form no part of the claimed design.
